UNITED STATES PATENT OFFICE.

WALDO DUANE TROW, OF KALISPELL, MONTANA.

RAILWAY-TIE.

1,191,044.

Specification of Letters Patent. Patented July 11, 1916.

Application filed February 9, 1916. Serial No. 77,220.

To all whom it may concern:

Be it known that I, WALDO DUANE TROW, a citizen of the United States, residing at Kalispell, in the county of Flathead and State of Montana, have invented new and useful Improvements in Railway-Ties, of which the following is a specification.

This invention relates to improvements in the construction of ties for railway rails.

10 An object of the invention is to produce a reinforced concrete tie constructed in such a manner as to withstand the shock and jar incident to the weight of the rolling stock passing thereover and to afford a resiliency 15 for the rails that will at least equal that of the ordinary wooden tie.

Another object of the invention is to construct a reinforced concrete tie with trough members to receive wooden or other resilient 20 cushion blocks upon which the rails rest, and to secure the said cushion blocks in the said troughs against accidental removal or displacement, but at the same time to permit of the removal of the said blocks when the 25 same become worn and are to be replaced.

A further object of the invention is to construct a flexible reinforced plastic tie having simple and practical means associated therewith whereby the rails may be effectively 30 secured thereon.

A still further object of the invention is to construct a reinforced plastic tie in such a manner that the rails will be cushioned thereon and insulated from the tie, so that 35 the operation of the signals will not be interfered with or the current flowing through the rails short circuited.

It is a still further object of the invention to provide a reinforced plastic tie which 40 shall be of a simple but strong and effective construction and which shall impart the desired amount of yieldability to the rails, and wherein the third rail of a three-rail system may be effectively connected with the ties.

45 With the above and other objects in view, the improvement resides in the construction, combination and arrangement of parts set forth in the following specification and falling within the scope of the appended 50 claims.

In the drawings: Figure 1 is a perspective view of rails supported upon ties constructed in accordance with the present invention, Fig. 2 is a greatly enlarged central longitudinal sectional view through one of the ties, Fig. 3 is a longitudinal sectional view

approximately on the line 3—3 of Fig. 2, Fig. 4 is a horizontal sectional view approximately on the line 4—4 of Fig. 3, Fig. 5 is a perspective view of a rail clamp which is adapted to be employed in connection with my tie, Fig. 6 is a central longitudinal sectional view through a modified form of the tie, Fig. 7 is a longitudinal sectional view through a still further modified form of the tie, Figs. 8 to 11 illustrate different manners in which the rail may be clamped upon the tie, and Figs. 12 to 16 are end views.

The tie is formed on or off the roadbed in a suitable mold, and before the concrete body is arranged therein I provide a central metallic strip which may have its ends offset in a vertical direction, as indicated by the numerals 2, and is straight for a suitable distance from the said offset ends, as indicated by the numeral 3, while an arched central portion 4 connects the said straight portions 3. Around the arched portion 4 and the vertical end 2 I arrange a wire mesh 5. The concrete 6, in the preferred form of my improvement is tamped to embrace the major portion of the arch 4 and the straight portions 3 and the angular ends 2 of the reinforcing member 1, leaving a space 7 at the center of the tie, and preferably the bottom 80 of the tie adjacent to the said center is cut-away in a curved line, as indicated by the numerals 8. By this arrangement it will be noted that the arched metal member 4 and the wire netting 5 are centrally exposed 90 and that the end portions of the tie are permitted to bend upon the said central portions of the metal members, so that when the tie is placed in the roadbed one of the ends thereof may move vertically independent of 95 the other, and as a consequence a yieldable tie is produced. However, and as illustrated in Fig. 6 of the drawings, the reinforcing members may be entirely inclosed by the plastic body 6 and also as noted in the said 100 figure, the central arched portion 4 of the reinforcing member 1 may be curved downwardly toward the lower face of the tie.

The straight portions 3 of the reinforcement 105 1 adjacent their angular ends 2 may be provided upon their under-faces with semi-cylindrical metal reinforcements 9, which are secured thereto by rivets 10, and these rivets also pass through the lower straight walls of transversely arranged 110 troughs 11. A sheet of fiber or other insulating material 12 is arranged between

the troughs and the straight portions 3 of the reinforcing member 1, and also flanged insulating collars 13 may surround the rivets and lie against the head portions thereof to insulate the troughs from the reinforcements. The troughs may have their sides inturned, as at 14, or cut to permit of the same being bent inwardly and so provide lips which engage with depressions 15 in the ends of the cushion blocks 17. The blocks 17 may be also secured in the troughs by spikes or nails 18 which are driven angularly through the side trough opposite the member 14, as illustrated in Fig. 3 of the drawings.

The sides of the troughs are preferably bent outwardly over but in a line with the upper face of the tie, and these bent portions are provided with longitudinally extending key hole slots 19' and the said bent portions or flanges indicated for distinction by the numeral 20 to one of the sides of the slot are formed with spaced apertures 21.

The numerals 22 indicate the rail engaging clamps which are shaped to lie upon the flanges of the rails 23 and which have their under-faces formed with T-head depending portions 24 that are adapted to be passed through the enlarged opening 21' of the key hole slot 19' to be slid longitudinally in the reduced portion of the said opening, and when in proper position retaining elements, such as pins or keys 25 are inserted through certain of the apertures 21.

The base of the rails may be surrounded by a sheet of insulating material 26, and this material may extend over the flange of the rails so that the rail engaging members or clamps 22 will lie upon the said sheet, and whereby the rail is effectively insulated from the tie.

By reference to the drawings it will be noted that the keyhole slots 19' are arranged at an inclination, and by this arrangement it will be noted that the rail clamps will be moved inwardly toward the webs of the rails, when the heads thereof are passed through the enlarged openings 21 of the slots and the said members moved in the direction of the opposite end of the slot. The inner or engaging end of the member 22 is preferably formed with a downturned lip 22', and as the head 24 of the member 22 will have a tendency to hold the said member in a horizontal position, the lip traveling upon the insulated material 26, arranged upon the said upper faces of the base flanges of the rails, will necessarily frictionally engage with the said material, forcing the same tightly against the rails, as will, it is thought, be readily understood.

The numerals 26' designate bolt members 65 which are arranged on one of the angular

ends 2 of the reinforcing member 1 and which project through one of the ends of the ties. These bolt members as well as the end of the tie have arranged thereon a sheet of insulating material 27, and the bolts are adapted to pass through openings in the vertical arm 28 of a bracket member 29 and the said arm is secured to the bolts by nuts 30. The head of the bracket comprises a channel member to receive the flange of a third rail 31 and the said flange may be secured to the bracket in any desired or preferred manner.

In Figs. 8 to 11 I have illustrated modified forms of means whereby the rail may be clamped upon the tie, and in Figs. 12 to 16 I have also illustrated various shapes in which the tie can be constructed.

In Fig. 7 the reinforcing member 1' comprises two elements 35 and 36 respectively, the same having their arched memberslapping and insulated from each other by a sheet of suitable material 36'. The arched members may be left uninsulated however. The overlapping ends are provided each with a plurality of spaced openings, which when certain of the same are brought into register are adapted to receive securing bolts 37 provided with locking nuts 38. By this arrangement it will be noted that while the strength of the reinforcing member is not materially affected, the ends of the ties may be adjusted toward or away from each other.

From the above description, taken in connection with the accompanying drawings, the simplicity of the device as well as the advantages thereof will, it is thought, be perfectly apparent to those skilled in the art to which such invention appertains without further detailed description.

Having thus described the invention, what I claim is:

1. A tie comprising two plastic spaced members having metal reinforcements connecting the same, a trough member arranged transversely of each of the plastic ends of the tie and supported upon but insulated from the metal reinforcement, a cushion block within each of the troughs, means upon the sides of the troughs for securing the cushion blocks therein, a rail adapted to rest upon but insulated from each of the blocks, and members associated with the troughs at the upper edges thereof for retaining the rails upon the blocks.

2. A tie for railway rails including a pair of spaced plastic members having metal reinforcements therein and extending through the inner ends of the same, means for adjustably connecting the extending ends of said reinforcements, troughs arranged in the plastic ends and connected to and insulated from the metal reinforcements, said troughs having their upper ends bent over the plastic members of the tie and their said ends pro-

vided with longitudinally extending key hole slots, and apertures disposed adjacent the slots, and said slots adapted to receive T-shaped depending members of rail-engaging elements, and pins passing through the apertures to retain the said elements upon the said ends of the trough.

3. A tie comprising spaced plastic members having their lower adjacent edges cut away, a metal reinforcement in each of the plastic members and projecting through the inner ends thereof, each of said reinforcements having a flat portion having one of its ends straight and bent upwardly in the tie adjacent the end of the tie and its opposite end straight and arched outwardly from the said flat portion and the ends of the arched and straight members adapted to overlap, means for adjustably connecting the said ends, a wire mesh wound around the arched and straight portions of the reinforcements, inverted U-shaped metal reinforcements arranged below and secured to the straight portions of the first mentioned

reinforcements, a substantially U-shaped trough arranged transversely in the plastic ends and secured to the straight portion of each of said reinforcements, a cushion block within each of the troughs to receive a rail, means between the sides of the trough and the cushion blocks for retaining the same in the troughs, means connected with the upper edges of the troughs for securing the rail upon the cushion block, means for insulating said securing members from the rails, bolt members connected with the angular end of one of the first mentioned reinforcing members and extending through the ends of one of the plastic members of the tie, and a rail supporting bracket connected to the said bolts.

In testimony whereof I affix my signature in presence of two witnesses.

W. DUANE TROW.
